(57) **CLAIM**

The ornamental design for a vertical card holder, as shown and described.

DESCRIPTION

FIG. 1 is a perspective view from the front, top and right of a vertical card holder, according to a first embodiment of the present invention;

FIG. 2 is right side view of the vertical card holder of FIG. 1, the left side being a mirror image;

FIG. 3 is a top view of the vertical card holder of FIG. 1;

FIG. 4 is a bottom view of the vertical card holder of FIG. 1;

FIG. 5 is a front view of the vertical card holder of FIG. 1;

FIG. 6 is a rear view of the vertical card holder of FIG. 1;

FIG. 7 is a perspective view from the front, top and right of a vertical card holder, according to a second embodiment of the present invention;

FIG. 8 is right side view of the vertical card holder of FIG. 7, the left side being a mirror image;

FIG. 9 is a top view of the vertical card holder of FIG. 7;

FIG. 10 is a bottom view of the vertical card holder of FIG. 7;

FIG. 11 is a front view of the vertical card holder of FIG. 7;

FIG. 12 is a rear view of the vertical card holder of FIG. 7;

FIG. 13 is a perspective view from the front, top and right of a vertical card holder, according to a third embodiment of the present invention;

FIG. 14 is right side view of the vertical card holder of FIG. 13, the left side being a mirror image;

FIG. 15 is a top view of the vertical card holder of FIG. 13;

FIG. 16 is a bottom view of the vertical card holder of FIG. 13;

FIG. 17 is a front view of the vertical card holder of FIG. 13; and,

FIG. 18 is a rear view of the vertical card holder of FIG. 13.

Broken lines show environmental details and form no part of the claimed design.
